TAMPER FOR CIGARETTE MACHINE FEEDS

Filed May 27, 1931

FIG. 2

INVENTOR
George Wilbur Gwinn
BY
Sydney A. Prescott
ATTORNEY

UNITED STATES PATENT OFFICE

GEORGE WILBUR GWINN, OF HEWLETT, NEW YORK, ASSIGNOR TO AMERICAN MACHINE
& FOUNDRY COMPANY, A CORPORATION OF NEW JERSEY

TAMPER FOR CIGARETTE MACHINE FEEDS

Application filed May 27, 1931. Serial No. 540,429.

This invention relates to an improvement in tobacco feeds for continuous rod cigarette machines, its main object being to provide improved means for tamping the tobacco to a homogeneous density on the tobacco feed drum so as to deliver a uniform shower of tobacco to the feed chute suspended over the rod-forming paper strip. The principal feature of this invention comprises an improved tobacco tamping device which constantly presses the tobacco to the feed drum in uniform density. With this and other objects not specifically mentioned in view, the invention consists in certain constructions and combinations which will be hereinafter fully described and then specifically set forth in the claims hereunto appended.

The improved tamper consists of a plurality of heavy compactor rings with toothed, fluted or corrugated peripheries which hang loosely side by side on a shaft extending across the entire tobacco hopper and rest on the tobacco, pressing the same by their weight against the revolving tobacco feed drum, thus assuring a compacted, even layer of tobacco between the pins of said drum, thereby eliminating bare and hollow spots.

The tobacco in the hopper not only tends to form an uneven surface on the feed drum but is of varying density along the same, especially when the hopper is newly filled; but the weight of the compactor rings compresses the tobacco against the feed drum and thus evens the density so that a uniform layer enters between the pins of the drum. The internal diameter of the compactor rings is much larger than the shaft upon which they are hung so that, no matter how uneven the surface of the tobacco on the feed drum, each portion of the surface receives an equal amount of compression. The supporting shaft of the compactor rings is mounted in two pivoted arms, thus forming a yieldingly mounted support for the compactor rings.

If desired, gears may be provided on the compactor ring supporting shaft, the external teeth of each gear engaging with the inner surface of one of the compactor rings, which for this purpose are provided with internal teeth. The shaft may be driven by

suitable means, thereby rotating the rings and producing a positive feed of the tobacco to the picker pins of the feed drum. This arrangement, however, may be dispensed with as the moving tobacco mass on the feed drum will cause the rings to turn.

In the accompanying drawings:

Fig. 1 is a fragmental sectional side elevation of a cigarette machine tobacco feed showing the improved tamping device; and

Fig. 2 is a sectional front elevation on line 2—2 of Fig. 1.

In carrying the invention into effect there is provided a tobacco feed drum, a support and a plurality of relatively large compactor rings surrounding the support and urged by gravity toward said drum. In the best forms of construction contemplated, the support includes a shaft supported by pivoted arms and provided with gears having external teeth meshing with internal teeth on the compactor rings. These various means and parts may be widely varied in construction within the scope of the claims for the particular device selected to illustrate the invention is but one of many possible concrete embodiments of the same. The invention, therefore, is not to be restricted to the specific construction shown and described.

The tobacco feed of a continuous rod cigarette machine consists of a tobacco hopper 5 in which revolves the carded tobacco feed drum 6 and the carded refuser or scraper drum 7, both rotating in the same direction. Feed drum 6 is equipped with picker pins 8 while scraper drum 7 carries scraper pins 9. Pins 8 pick up the tobacco T in the hopper 5 and pins 9 scrape the surplus protruding from the pins 8, allowing only the tobacco in the picker pin spaces to be carried away by the feed drum 6.

A shaft 10 placed above feed drum 6 is suspended by arms 11 pivoted on studs 12 mounted in the side frames 13 of the hopper, the arms 11 resting on stops 14 when the hopper is empty. Shaft 10 carries a pulley 15 driven through a belt 16 from a pulley 17 on stud 12 which is connected by a belt 18 with the main drive of the machine.

Along the entire length of shaft 10 within

the hopper 5 are provided gears 19 separated from each other by narrow spacer discs 20. Upon each of these gears is hung a heavy ring 21 having an internal diameter much 5 larger than the diameter of the gears 19 and provided with internal teeth 22 meshing with the external teeth of the gears 19. When the hopper is filled, the rings 21 rest on the irregular surface of the tobacco on the feed 10 drum, and, owing to their large internal clearance, not only can readily find their level but can go up and down with the tobacco mass which varies during the run of the machine. Thus, each ring bears on the varying tobacco 15 mass with an equal pressure at all times, producing a uniformly compacted tobacco layer at the surface of the mass and, since this layer is constantly pressed by the compactor rings into the spaces between the pins 8 of the feed 20 drum 6, all the pins of the latter will pick up equal amounts of tobacco, insuring an even and homogeneous layer on the same.

The spacer discs 20, which guide the movement of the compactor rings, are made large 25 enough to cover the internal clearance of the compactor rings, thus preventing tobacco from entering the ring holes, and the end discs 23 have a diameter sufficient to cover up the slots 24 provided in the end walls of tobacco chamber 5 to receive the ends of the shaft 10 and permit upward motion of the 30 pivoted arms 11 whenever the mass of tobacco on the feed drum accumulates sufficiently 35 to press the compactor rings upwardly against the gears 19 on shaft 10.

To prevent tobacco in a newly filled hopper from reaching the scraper drum 7 over the tops of the compactor rings, a revolving rake 25 is provided which extends across the entire 40 width of the hopper.

Since the rotation of the feed drum 6 causes the tobacco mass in contact with it to partake of its motion, the compactor rings, which bear on this moving mass, will also be rotated so 45 that it will ordinarily not be necessary to rotate the same by positive means. Therefore, the gears 19 and the driving means 15, 16, 17 and 18 of shaft 10 may be omitted and the compactor rings made with smooth internal 50 surface resting directly on shaft 10, in this manner greatly simplifying the arrangement.

What is claimed is:

1. The combination with a tobacco feed drum, of a support arranged above said drum, and a plurality of relatively large compactor rings surrounding said support and urged by gravity toward said drum.

2. The combination with a tobacco feed drum, of a support yieldingly mounted above 60 said drum, and a plurality of relatively large compactor rings surrounding said support and urged by gravity toward said drum.

3. The combination with a tobacco feed drum, of a support yieldingly mounted above 65 said drum, and a plurality of relatively large

compactor rings surrounding said support and urged by gravity toward said drum, said rings being provided with internal teeth, and said support including a shaft and external teeth meshing with said internal teeth. 70

4. The combination with a tobacco feed drum, of a support yieldingly mounted above said drum, and a plurality of relatively large compactor rings surrounding said support and urged by gravity toward said drum, said 75 support including a shaft provided with pivoted arms for supporting it.

5. The combination with means for providing a supply of tobacco, of a carded tobacco feed surface passing through the supply, a 80 support arranged above and transversely of said surface, and a row of compactor rings loosely surrounding said support for independent movement by gravity toward the tobacco supply overlying said surface. 85

6. The combination with a tobacco feed drum, of a support arranged above said drum, a plurality of compactor rings loosely surrounding said support for independent movement toward and away from the drum and disks fitting said support between said rings 90 for preventing one of said rings from communicating said movement to the adjacent rings.

In testimony whereof, I have signed my 95 name to this specification.

GEORGE WILBUR GWINN.
